UNITED STATES PATENT OFFICE.

JAMES E. GILBERT AND GLENN W. HARRIS, OF CHICAGO, ILLINOIS.

SECTIONAL SMUT SHEET AND CROSSBAR FOR SMUT-SHEET MACHINES.

Application filed May 17, 1920. Serial No. 382,142.

To all whom it may concern:

Be it known that we, JAMES E. GILBERT and GLENN W. HARRIS, citizens of the United States, residing at Chicago, county of Cook, and State of Illinois, have invented a certain new and useful Improvement in Sectional Smut Sheets and Crossbars for Smut-Sheet Machines, of which the following is a specification.

10 Patent Number 966,739 to J. E. Gilbert, issued August 9, 1910, illustrates and claims a machine for taking care of sheets of printed or lithographed matter between the time they receive the impression of ink and the 15 time they are sufficiently dried to prevent offsetting when placed on a pile. Broadly speaking that machine includes the use of an intermittently moving and successively folding strip of cloth between which successive sheets 20 of printed paper are placed immediately on being printed, and in which they are carried until sufficiently dry to be automatically delivered from the machine, all as will more fully appear from the inspection of said 25 patent.

In that machine a section of a continuous strip of cloth is temporarily stretched between supports during which time it is referred to as a "print sheet support." While 30 this section of cloth is being fed into position in the support the paper to be taken care of travels along and is carried by it to the position where it is to be "smutted" by the succeeding section of cloth. The next 35 section of cloth spread over the paper on the print sheet support is denominated a "smut sheet."

In the machine of said prior patent, the "print sheet support" and the "smut sheet" 40 are in fact one continuous piece of cloth and carry at their juncture a metallic cross bar designated "52," in said patent, pivoted to the continuous cloth on a single hinge. This construction is for the purposes of allowing 45 the bar to be temporarily supported in and passed down vertical guides 44 or 45 as the case may be, of said patent while the smutting operation is taking place with the print sheet support and the smut sheet parallel to 50 and adjacent to each other and at right angles to said support as is clearly shown and set forth in said prior patent. When the smutting operation is not taking place in the machine of said prior patent, the two

sections of cloth straighten out in alignment 55 with each other for the purpose of traveling over different rollers provided in the machine, and the bar is merely suspended from the continuous cloth by the hinge—this for the purpose of transferring the cloth and bar from the bottom of the machine to the top of the machine, as is fully set forth in said prior patent.

The use of the continuous strip of cloth as set forth in said prior patent in a machine of the type in question has several disadvantages—(a) if a section of the cloth gives out in operation either from wear or from injury from the outside, the only way it can be replaced is to stop the machine, cut 65 out the injured section and sew in a new section. Owing to the breadth of the cloth strip used in commercial practice varying from 64 to 72 inches, and the fact that the cloth carries metallic cross-bars at frequent 70 intervals, it is impossible to apply a sewing machine in this operation, and it therefore has to be done by hand at an expense of approximately two hours' time in actual practice which means the tying up of the entire 80 printing unit with which the machine is co-operating. (b) Different sections of cloth obviously get dirty faster than others, and in the prior machine it is impossible to clean a section without making the entire strip of 85 cloth off the machine and cleaning it as a whole and in the same way it is impossible to reverse the cloth if one side becomes dirty in the smutting operation, as is apt to be the case, to use the other side before cleaning 90 the whole cloth.

The object of this invention is to provide what is for practical purposes in the running of the machine, a continuous strip of smut sheet cloth with bars attached thereto 95 and to so construct it that the sections of cloth between successive bars are separate units and may therefore be readily removed for repair, cleaning or replacement. A further object of the invention is to provide 100 a satisfactory and efficient bar construction which facilitates the ready attachment and detachment of the adjacent sections of cloth.

The invention consists in means for carrying out the foregoing objects which can be 105 easily and cheaply made, which is satisfactory in operation and not readily liable to get out of order. More particularly the in-

vention consists in features and details of construction more fully set forth in the specification and claims.

Referring to the drawings in which similar numerals denote the same parts throughout the several views,

Figure 1 is a plan view of a cross bar constructed in accordance with this invention in its preferred form, showing in broken 10 away from the adjacent portions of smut sheet cloth attached thereto.

Figure 2 is an enlarged detail view of the end portions of Figure 1, showing particularly the details of the construction of the 15 end of the bar and the pivotal attachment to the cloth.

Figure 3 is an end view of a bar and adjacent portions of cloth in the position which it assumes for traveling from the bottom of 20 the machine to the top.

Figure 4 is a sectional detail view on the irregular line 4-4 of Figure 2 showing attachment of adjacent sections of cloth to the bar, the parts being in the position which 25 they assume when the smutting operation is taking place, with the bar in the vertical guides of the machine.

Figure 5 is a sectional end view on the line 5-5 of Figure 2.

Figure 6 is a sectional end view on the line 6-6 of Figure 2.

The preferred form of bar shown in the drawing is made of hollow construction for the purpose of obtaining lightness and 35 rigidity. In the particular form shown in the drawing it is made of U-shaped cross section with two relatively wide, parallel sides 10 and a bottom 12, the interior of the section being open at the top toward the adjacent portions of cloth 14 and 16 which are, 40 as clearly shown in the drawings, independently hinged to the bar on parallel wires 18 and 20, detachably insertable on hinge brackets 22, projecting from the edge 24 of the bar. These brackets 22 serve a double 45 function; portions of them as described, extend from the edge of the bar and afford supports or bearings for the rods 18 and 20, while the remaining portions of them designated in Figure 4, 22*, extend between the edge 24 of the bar and act as separators for the side plates 10 of the bar. These separators are secured in place by tubular rivets 26 which pass through the side plates 10 and 55 the separators.

The extreme ends of the bar are strengthened and reinforced by making the end sections of the bar a rectangular tube through insertion of filler plates 28 secured in place 60 by other tubular rivets 30 like rivets 26. This strengthening of the ends of the bar is necessary in order to enable them to withstand the action of parts of the complete machine which handles the ends of the bar 65 in placing them in the vertical guides; here-

tofore referred to. These filler blocks 28 serve the further function of rendering the edge 24 of the bar smooth at the points where it engages and slips upon the guides of the machine in passing down them. 70

It is clear from the foregoing description and the drawings that either one of the cloth sections 14 or 16 may be disconnected from the particular bar shown in the drawing by removing its hinge rod 18 or 20 as the case 75 may be, and a new section of cloth be substituted therefor; it being of course understood that such new section of cloth has been previously prepared with a loop 31 through which the hinge rod can pass. In 80 the particular case here illustrated these edge loops for the hinge rods are made by simply bending an edge 32 of cloth backward on the cloth proper and sewing it with a machine parallel to the rod, as for instance 85 in the seam 34.

A complete smut sheet belt, referred to, is made up by using successive sections of cloth 14 and 16 having on their opposite ends loops 31 for the hinge wires described 90 and connecting adjacent sections of cloth together by hinge structures such as shown in the drawing. Such a belt can in the manner described, have a section of cloth replaced by simply detaching the opposite 95 edges of that particular section from the adjacent bars and substituting a new section of cloth. In actual practice in a commercial machine this can be done in approximately ten minutes, or less. 100

Having thus described our invention what we claim as new and desire to secure by Letters Patent, is:—

1. In mechanism of the class described, a smut sheet cloth including two sections of cloth placed end to end, a transverse bar of greater length than the width of the smut sheet, and means detachably hinging each section of the cloth to the bar. 105

2. In mechanism of the class described, a smut sheet cloth including two sections of cloth placed end to end, a transverse bar of greater length than the width of the smut sheet, and means independently detachably hinging each section of the cloth to the bar. 110

3. In mechanism of the class described, a smut sheet cloth including two sections of cloth placed end to end, a transverse bar of greater length than the width of the smut sheet, and parallel hinge means independently detachably hinging each section of the cloth to the bar. 115

4. In a device of the class described, a smut sheet including two separate sections of smut sheet cloth placed end to end, the adjacent edge of each cloth section being provided with means for the insertion of a hinge rod therein, a bar extending transversely of the smut sheet adjacent to the point of juncture of the cloth sections, and 120

130

means for detachably hinging the cloth sections to the bar through said loops on attaching.

5. In mechanism of the class described, a pair of aligned cloth sections, a bar extending across the cloth at the point of juncture of said sections, a pair of parallel hinges on the bar, one detachably connecting one hinge to each cloth section, for the purposes set forth.

10 6. In mechanism of the class described, a pair of abutting cloth sections, both provided on their adjacent edges with loops through which hinged pivot hinges can pass, a bar across the cloth sections adjacent to said loops, a hinged support including a hinged pivot bar or rod rising from the main bar, one for each of said cloth sections, for the purposes set forth.

15 7. In mechanism of the class described, a cross bar made of metal of U-shaped cross section, the open edge of the bar being closed at its ends by filler blocks 28 while the central portion of the bar carries in its

20 open edge spacing members 22^a from which project wings, this in combination with hinged pivot rods to said wings, for the purposes set forth.

8. In mechanism of the class described, a cross bar of U-shaped metal, a pair of separated spacing members 22^a inserted within the open edge of the bar and secured to the bar by rivets 26, a projecting plate 20 carried by each member 22 extending from the edge of the bar at right angles thereto, a 30 pair of hinge rods 18 and 20 connecting said plates 22, and sections of smut sheet cloth pivotally connected on said hinge rods and extending to opposite sides of the bar, for the purposes set forth.

40 In witness whereof we have hereunto subscribed our names.

JAMES E. GILBERT.
GLENN W. HARRIS.
